(57) **CLAIM**

The ornamental design for double-sided jewelry setting, as shown and described.

DESCRIPTION

FIG. 1 is a top plan view of a double-sided jewelry connector showing my new design;

FIG. 2 is a top end elevational view;

FIG. 3 is a left side elevational view;

FIG. 4 is a bottom plan view;

FIG. 5 is a right side elevational view; and,

FIG. 6 is a bottom end elevational view.

The broken line showing of gemstones and mountings are for illustrative purposes only and forms no part of the claimed design.
